UNITED STATES PATENT OFFICE.

FRANCIS E. DRAKE, OF DAVENPORT, IOWA.

HOIST.

1,426,264.

Specification of Letters Patent. Patented Aug. 15, 1922.

Application filed November 21, 1921. Serial No. 516,722.

To all whom it may concern:

Be it known that I, FRANCIS E. DRAKE, a citizen of the United States, residing at Davenport, in the county of Scott and State 5 of Iowa, have invented certain new and useful Improvements in a Hoist, of which the following is a specification.

The invention has reference to machines or apparatuses for lifting or hoisting heavy 10 objects and has for its principal object to provide a device of this character which contains certain improved features serving to strengthen the device and greatly increase its utility attention being called to the 15 structure disclosed in the Patent Number 1,413,526 issued to me on April 18, 1922.

With the above and numerous other objects in view as will appear as the description progresses, the invention resides in certain 20 novel features of construction, and the combination and arrangement of parts as will be hereinafter more fully described and claimed.

In the drawing:—

25 Figure 1 is a side elevation of a hoist constructed in accordance with the invention,

Figure 2 is a top plan thereof,

Figure 3 is a front elevation thereof.

30 Figure 4 is a detailed view of the guide roller and bracket used in connection with the device,

Figure 5 is a similar view taken at right angles to that shown in Figure 4, and

35 Figure 6 is a plan view of a plate used in conjunction with the device.

Referring to the drawing in detail it will be seen that 1 designates a base which is of substantial U-shaped construction. The 40 brackets 2 are provided at the terminals of the base 1 and have journalled therein the wheels 3 which are disposed so as to be in alignment with the legs of the base. A pair of bridge plates 4 are fixed to the base and each is preferably situated adjacent the 45 corners thereof as shown to advantage in Figure 2. The castor rollers 5 are suitably attached to the bridge plates 4 intermediate their ends whereby the base 1 may be moved from place to place as will be readily understood.

In the preferred construction of the frame work of this device, I provide three standards projecting upwardly from the base two 55 of which are located intermediate the ends of the legs thereof and the other at the cen-

ter point of the base. The side standards 6 have the brace elements 7 fixed thereto at their bottom ends and also to the legs of the base 1. Similar brace elements 8 60 are attached in like manner to the end standard 9. A cross beam 10 extends across the top of the standards 6 and the brace elements 11 are connected to the cross beam 10 and the legs 6 as is seen to advantage in 65 Figure 3. The parts thus far described form the frame work of the invention upon which the hoisting mechanism is mounted.

A supporting beam 12 is disposed between the standards 6 and has fixed to its terminals the journal brackets 13 which support the guide rollers 14 that are adapted to move in the groove formed in the standard 6. All the parts of the frame work are preferably constructed of I-beams. Any 75 suitable means may be provided for lifting the supporting beam 12. I prefer, however, to provide the conventional and well known chain hoist as indicated at 15. The lifting chain 16 is actuated by the chain hoist 80 15 and is connected at one end to the intermediate portion of the supporting beam 12 so that the same may be raised and lowered when desired.

Lift means are supported on the supporting beam 12 and consists of a pair of lift arms 19 which are fulcrumed at their rear ends between a link plate 20 and a plate 21. These rear ends of the lifting arms 19 are preferably slightly spaced from each 90 other. The plate 21 comprises an elongated body having a slot 22 therein and at its rear end is provided with the apertured diverging ears 23 to which the rear ends of the lifting arms 19 are fulcrumed. At its other 95 end the plate 21 is provided with the diverging arms 24 which are provided with the right angularly extending ears 25 that may be suitably attached to the supporting beam 12. A pair of links 27 are fulcrumed 100 together at one of their ends and preferably by a pin which is adapted to extend through the slot 22. The other ends of the links 27 are fulcrumed to the lifting arms 19 intermediate their ends so that these arms will at 105 all times be equi-distant from their respective adjacent legs of the base 1 when they are moved in a horizontal plane. Thus, referring to Figure 2, if one arm 19 is moved inwardly the other arm 19 will be moved 110 inwardly an equal distance.

The brackets 30 are fixed to the ends of

the lifting arms 19 and are provided with the arcuate edges 31 so that an axle of an automobile or the like may readily rest therein. An equalizing device is associated 5 with the inner or pivoted terminals of the arms. It comprises an equalizing cable 32 having its terminals suitably attached to the eye-bolts 33 carried respectively by the link plate 20 and the supporting bar 12. This 10 cable is passed over sheave wheels 34, 35, and 36. As shown in the drawing there is preferably provided two of these equalizing chains 32 that are connected to the supporting beam 12 at equal distances from its 15 center. This equalizing arrangement tends to keep the lifting arms in a horizontal position at any and all times holding them balanced upon the supporting beam 12 at all stages in its vertical adjustment.

20 A leg 40 is provided with a curved extension 41 which is fulcrumed to each of the lifting arms 19 adjacent their free ends and may be held in an inactive position by the latch hooks 42 which are fulcrumed on the 25 bottom of the lifting arms as at 43 the other end of their bases adapted to engage the stop bolts 44. These legs are preferably used when a load is to be left in a lifted position for some time such as the raising 30 of the forward end of an automobile at which time the lifting bars will be raised the height of the legs 40 at which time they may be placed in a vertical position so as to engage the floor and support the arms 35 thus releasing most of the strain from the frame of the device.

The foregoing description and accompanying drawings have reference to what might be considered the approved or preferred form of my invention, I desire it to 40 be understood that I may make such changes in the construction, combination and arrangement of parts, materials, dimensions, et cetera, as may prove expedient and fall 45 within the scope of the invention as hereinafter claimed.

Having thus described my invention what I claim as new is:-

1. A hoist comprising a frame having a 50 movable guide, lift arms fulcrumed on said guide and horizontally adjustable, a plate extending from said movable guide and having the ends of said lift arms pivoted thereto, a pair of links pivoted at one end 55 to each other, a pin passing through the pivoted ends of the links, said plate provided with a slot for receiving said pin, the other ends of the links being pivoted to the respective lift arms intermediate their ends.

60 2. A hoist comprising a frame having a

movable guide, lift arms fulcrumed on said guide and horizontally adjustable, a plate extending from said movable guide and having the ends of said lift arms pivoted thereto, a pair of links pivoted at one end 65 to each other, a pin passing through the pivoted ends of the links, said plate provided with a slot for receiving said pin, the other ends of the links being pivoted to the respective lift arms intermediate their ends, 70 and means for moving the guide to adjust the lift means vertically.

3. In combination, a frame, a supporting beam movable vertically in the frame, means for moving the supporting beam, a 75 pair of lift arms resting intermediate their ends on said supporting beam, a plate extending from said supporting beam and provided with a longitudinal slot therein, one of the ends of each lifting arm fulcrumed 80 on the plate, a pair of links, a pin passing through the ends of said links and through said slot and the other ends of the links being connected to the supporting beam.

4. A hoist comprising a frame having a 85 movable guide, lift means fulcrumed on said guide and horizontally adjustable, means for moving the guide to adjust the lift means vertically, and legs pivoted to the lift means in the manner and for the purpose 90 specified.

5. A hoist comprising lift arms pivotally fixed at corresponding ends with their respective outer or weight supporting ends movable in a horizontal plane, a vertically 95 adjustable member below the lift arms and providing a fulcrum support therefor, and legs pivotally carried by the lift arms in the manner and for the purpose specified.

6. A hoist comprising lift arms, a vertically adjustable member below the lift arms, so as to support the same, a plate fixed to the vertically adjustable member and provided with a slot therein, corresponding ends of the lift arms being pivotally attached to the plate, links pivoted to the arms intermediate their ends and pivoted to each other, a pin passing through the pivoted ends of the links and through the slot in said plate for keeping the arms equidistant 100 from a central point on the vertically adjustable member, and means for holding the arms in horizontal position at any and all times.

In testimony whereof I affix my signature 115 in presence of two witnesses.

FRANCIS E. DRAKE.
